2 Sheets-Sheet 2

UNITED STATES PATENT OFFICE.

FRANK T. STUART, OF MAPLEWOOD, NEW JERSEY, ASSIGNOR TO THE R. NEUMANN HARDWARE CO., A CORPORATION OF NEW JERSEY.

BAG-FRAME FASTENER.

Application filed August 12, 1924. Serial No. 731,624.

To all whom it may concern:

Be it known that I, FRANK T. STUART, a citizen of the United States, residing at Maplewood, in the county of Essex and

5 State of New Jersey, have invented certain new and useful Improvements in Bag-Frame Fasteners; and I do hereby declare the following to be a full, clear, and exact description of the invention, such as will 10 enable others skilled in the art to which it appertains to make and use the same, reference being had to the accompanying drawings, and to characters of reference marked thereon, which form a part of this specification.

15 This invention relates, generally, to improvements in bag-frame fasteners, and, the present invention has reference, more particularly, to a novel construction of safety-catch for the hinged frame-sections of a bag-frame, with a view of providing a simply constructed and positively acting construction, the parts of the fastener having been reduced to a minimum, and the 20 parts of the fastener being arranged so that they will act automatically to maintain a locked relation of the parts of the fastener, when the hinged bag-frame sections are closed, but being readily manipulated, to bring the parts of the fastener into their unlocked relation, so that the frame-sections 25 may be brought into their separated or opened relation.

30 The present invention, therefore, has for its principal object to provide a bag-frame fastener of the general character and construction hereinafter more fully set forth, and having for its main purpose an automatic locking action of its mechanism for maintaining the bag-frame sections in their 35 closed relation.

40 Other objects of the present invention not at this time more particularly enumerated will be clearly understood from the following detailed description of the present invention.

45 With the various objects of the present invention in view, the said invention consists, primarily, in the novel bag-frame fastener hereinafter more fully set forth; and, the invention consists, furthermore, in the novel arrangements and combinations of the devices and parts, as well as in the details of the construction of the said parts, 50 all of which will be more fully described in

the following specification, and then finally embodied in the clauses of the claims, which are appended to and which form an essential part of the said specification.

The invention is illustrated in the accompanying drawings, in which:—

55 Figure 1 is a top edge-view of the two frame-sections of a bag-frame, said frame-sections being shown in their disconnected relation, one of said frame-sections illustrating in connection therewith an arrangement of a pair of fasteners embodying the principles of the present invention, and the other frame-section being shown with a pair of hasp-members adapted to be moved into 60 locking engagement with the mechanism of said fasteners, the push-members or bolts of the fasteners being represented in their manually actuated positions for releasing the hasp-members from their locked engagement with the mechanism of the fasteners.

70 Figure 2 is a top-edge view of a portion of the frame-section provided with the frame-fasteners, showing in connection therewith a fastener having its push-member 75 or bolt in the position, when the parts of the inner mechanism of the fastener are in locked relation with one another.

75 Figure 3 is a top-edge view of a fragmentary portion of the frame section, and a bottom or base-plate secured thereto, the main shell or casing of the fastener, with its contained mechanism, being omitted from said view; and Figure 4 is a similar view of 80 one portion of the frame-section represented in said Figure 3, with the bottom or base-plate removed from the frame-section.

85 Figure 5 is a transverse vertical sectional representation taken on line 5—5 in Figure 1; Figure 6 is a horizontal sectional representation of the various parts, said section being taken on line 6—6 in said Figure 5, looking in the direction of the arrow *x*; Figure 7 is a view, similar to said Figure 6, 90 illustrating the inner mechanism of the fastener in its locked engagement with the hasp-member; and Figure 8 is a longitudinal vertical section of the device, said section being taken on line 8—8 in said Figure 5, looking in the direction of the arrow *y*.

100 Figure 9 is a perspective view of the push-member or bolt of the said bag-frame fastener; and Figure 10 is a similar view of the base-plate of the same.

105 Figures 11 and 12 are views, similar to 110

Figures 6 and 7, respectively, of a modified construction of bag-frame fastener.

Similar characters of reference are employed in all of the said above-described views, to indicate corresponding parts.

Referring now to the several figures of the drawings, the reference-characters 1 and 2 indicate the frame-sections of a bag-frame, which are of any of the usual constructions, 10 and which are adapted to be pivotally connected in the usual and well-known manner. To one of said frame-sections, as 2, is suitably secured by means of rivets 3, or otherwise, a hasp-plate 4 having an upwardly extending member 5 from which extends, at a right angle, a hasp-member 6 provided with a laterally extending receiving notch or slot 7, and a spring-engaging end-portion 8, substantially as shown in the 20 several figures of the drawings, the same being adapted to be moved over and above the frame-section 1 and enter the shell or casing of the bag-frame fastener for engagement with the hasp-engaging mechanism within said shell or casing, in the manner to be presently more fully described.

The form of bag-frame fastener shown more particularly in Figures 1 to 10 inclusive, consists, essentially, of a main shell or casing comprising a top 9, a pair of longitudinally extending side-walls 10 and 11, and a pair of end-walls 12 and 13, one of said side-walls, as 10, being provided with a suitably disposed opening, as 14, and the 30 said end-walls 12 and 13 being respectively provided with fastening lugs 15, which extend into and are passed through correspondingly shaped slits or openings 17 of a base-plate 16 disposed against the marginal edges of the side-walls 10 and 11, and the end-walls 12 and 13, of the said shell or casing, as indicated in Figures 5 and 8 of the drawings. That the said shell or casing, with its base-plate 16, may be secured 40 upon the outer face of the frame-section 1, the said fastening lugs 15, are also passed through correspondingly located slits 18 in the frame-section 1 and then bent over upon the under face of said frame-section, in a manner as indicated in said Figures 45 and 8 of the drawings.

The reference-character 19 indicates a suitably shaped bolt, in the form of a push or slide-plate, which is longitudinally disposed within the chamber of the said shell or casing, the said plate having its respective end-portions 20 and 21 extending into and through suitably disposed guiding openings or slits 22 and 23 in the respective end-walls 12 and 13 of the said shell or casing, and the projecting parts of the said end-portions 20 and 21 being respectively provided with angular members 24 and 25, one of which, as 24, serves as a push or fingerpiece, and the other member 25

serving as a stop, as will be evident more particularly from an inspection of Figure 7 of the drawings. In addition, the push or slide-plate 19 is provided with a pair of suitably disposed studs or posts 26 and 27, 70 and also with a projecting portion 28, which is provided with a hasp-engaging flange 29, one end of which, nearest the end-wall 13 of the shell or casing, is provided with a bent portion, as 30.

Disposed between the inner face of the said end-wall 13 and the said bent portion 30 are the arms or members of a U-shaped spring 31. The reference-character 32 indicates another spring, comprising a pair of arms or members 33 and 34, connected by means of an angularly formed portion 35, and with the edge-portion 36 of which, under normal conditions, when the frame-sections 1 and 2 have been brought into 85 their closed relation, the spring-engaging end 8 of the hasp-member 6 has been brought into engagement.

Referring now to Figure 6 of the drawings, in which the parts of the inner mechanism are shown in their manually operated positions, when the slide-plate 19 has been forced by the operator exerting pressure upon the push or fingerpiece 24 in the direction of the arrow α , and in which figure the hasp-member 6 is shown in its withdrawn relation from the said mechanism, the parts of the mechanism being held in the positions shown by the engagement of the portions 36 and 33 of the spring 32, 100 respectively, with the studs or posts 27 and 26, as soon as the hasp-member 6 enters the opening 14 in the side-wall 10, as the frame-sections are being closed, the portion 8 engages the edge-portion 36 of the spring 32, thereby forcing the angular portion 35, clear of the stud or post 27. Immediately, the compressed members or arms of the spring 31 become active, thereby causing the slide-plate 19 to be moved into the position indicated in Figure 7 of the drawings, with the hasp-engaging flange 29 of the said plate having entered the notch or slot 7 of the hasp-member, so that all of the various parts, as well as the closed frame-sections 1 and 2 will be maintained in their closed and locked relation.

The stop-member 25 in coming in contact with the outer face of the end-wall 13 of the shell or casing limits the closing movement of the slide-plate 19, as will be clearly evident. To again bring the frame-sections 1 and 2 into their open relation, and to separate the hasp-member 6 from its locked engagement with the flange 29 of the slide-plate 19, all that the operator has to do is to apply pressure upon the push or fingerpiece 24, thereby changing the relative positions of the parts of the mechanism, as indicated in Figure 7 of the draw- 125

ings, to the positions shown in Figure 5 of the drawings.

Referring now to the modified construction of bag-frame fastener, shown in Figures 11 and 12 of the drawings, the general arrangement of the several parts of the mechanism is the same as that herein-before described, except that the push or slide-plate 19 in this construction is provided with 10 but a single stud or post, as 37, with which the angular portion 35 of the spring 32 is adapted to engage, as shown in Figure 11, the shell or casing, in this instance, being provided with a third spring 38 secured to 15 the inner face of the side-wall 10, as at 39, the free end-portion of this spring bearing forcibly upon an edge-portion 40 of the hasp-member 6, when the various parts are in their locked relation, as indicated in 20 Figure 12 of the drawings, but said spring 38 permitting the hasp-plate to be operated when the slide-plate 19 is manually manipulated, as previously described, and for the release of the said hasp-member with the 25 engaging flange 29 of the said slide-plate, as will be fully understood from an inspection of said Figures 11 and 12 of the drawings.

Of course I am aware that the device is 30 capable of other changes in the general arrangements and combination of the devices and parts, as well as in the details of the construction of the same, without departing from the scope of the present invention, as 35 set forth in the foregoing specification, and as defined in the clauses of the claims which are appended thereto. Hence, I do not limit my present invention to the exact arrangements and combinations of the said devices 40 and parts, as described in the said specification, nor do I confine myself to the exact details of the construction of the said parts, as illustrated in the accompanying drawings.

45 I claim:—

1. A bag-frame fastener comprising a chambered shell having a top, longitudinally extending side-walls, one of said side-walls being provided with a hasp-receiving opening, and end-walls, said end-walls being provided with guiding openings, a reciprocatory slide-plate within said chambered shell, said slide-plate having its respective end-portions projecting into and from the 50 respective guiding openings in said end-walls, means connected with said slide-plate for engagement with a hasp, means within the shell co-operating with the said slide-plate for maintaining the same in its manually released position, and additional means within said shell for automatically returning the slide-plate to its initial position upon entrance of the hasp into said shell.

60 2. A bag-frame fastener comprising a

chambered shell having a top, longitudinally extending side-walls, one of said side-walls being provided with a hasp-receiving opening, and end-walls, said end-walls being provided with guiding openings, a reciprocatory slide-plate within said chambered shell, said slide-plate having its respective end-portions projecting into and from the 70 respective guiding openings in said end-walls, means connected with said slide-plate for engagement with a hasp, lugs connected with and extending from said slide-plate, a spring within said shell having portions thereof in engagement with said lugs, for maintaining the slide-plate in its manually released position, and means within said shell for automatically returning the slide-plate to its initial position upon entrance of the hasp into said shell.

75 3. A bag-frame fastener comprising a chambered shell having a top, longitudinally extending side-walls, one of said side-walls being provided with a hasp-receiving opening, and end-walls, said end-walls being provided with guiding openings, a reciprocatory slide-plate within said chambered shell, said slide-plate having its respective end-portions projecting into and from the 80 respective guiding openings in said end-walls, means connected with said slide-plate for engagement with a hasp, lugs connected with and extending from said slide-plate, a spring within said shell having portions thereof in engagement with said lugs, for maintaining the slide-plate in its manually released position, and means within said shell for automatically returning the slide-plate to its initial position upon entrance of the hasp into said shell.

85 4. A bag-frame fastener comprising a chambered shell having a top, longitudinally extending side-walls, one of said side-walls being provided with a hasp-receiving opening, and end-walls, said end-walls being provided with guiding openings, a reciprocatory slide-plate within said chambered shell, said slide-plate having its respective end-portions projecting into and from the 90 respective guiding openings in said end-walls, a fingerpiece connected with one of the projecting end-portions of the slide-plate, and a stop-member connected with the other projecting end-portion of said slide-plate, means connected with said slide-plate for engagement with a hasp, means within said shell co-operating with said slide-plate for maintaining the same in its manually released position, and additional means within said shell for automatically returning the slide-plate to its initial position upon entrance of the hasp into said shell.

100 5. A bag-frame fastener comprising a chambered shell having a top, longitudinally extending side-walls, one of said side-walls being provided with a hasp-receiving open-

ing, and end-walls, said end-walls being provided with guiding openings, a reciprocatory slide-plate within said chambered shell, said slide-plate having its respective end-portions projecting into and from the respective guiding-openings in said end-walls, a finger-piece connected with one of the projecting end-portions of the slide-plate, and a stop-member connected with the other projecting end-portion of said slide-plate, means connected with said slide-plate for engagement with a hasp, lugs connected with and extending from said slide-plate, a spring within said shell having portions thereof in engagement with said lugs, for maintaining the slide-plate in its manually released position, and means with said shell for automatically returning the slide-plate to its initial position upon entrance of the hasp into said shell.

6. A bag-frame fastener comprising a chambered shell having a top, longitudinally extending side-walls, one of said side-walls being provided with a hasp-receiving opening, and end-walls, said end-walls being provided with guiding openings, a reciprocatory slide-plate within said chambered shell, said slide-plate having its respective end-portions projecting into and from the respective guiding-openings in said end-walls, a fingerpiece connected with one of the projecting end-portions of the slide-plate, and a stop-member connected with the other projecting end-portion of said slide-plate, means connected with said slide-plate for engagement with a hasp, lugs connected with and extending from said slide-plate, a spring within said shell having portions thereof in engagement with said lugs, for maintaining the slide-plate in its manually released position, and an additional spring within said shell for automatically returning the slide-plate to its initial position upon entrance of the hasp into said shell.

45 7. A bag-frame fastener comprising a chambered shell having a top, longitudinally extending side-walls, one of said side-walls being provided with a hasp-receiving opening, and end-walls, said end-walls being provided with guiding openings, a reciprocatory slide-plate within said chambered shell, said slide-plate having its respective end-portions projecting into and from the respective guiding openings in said end-walls, a fingerpiece connected with one of the projecting end-portions of the slide-plate, a stop-member connected with the other projecting end-portion of the slide-plate, and a marginal hasp-engaging flange connected with and extending downwardly from said slide-plate, means within said shell co-operating with said slide-plate for maintaining the same in its manually released position, and additional means with-
60
65 in said shell for automatically returning the

slide-plate to its initial position upon entrance of the hasp into said shell.

8. A bag-frame fastener comprising a chambered shell having a top, longitudinally extending side-walls, one of said side-walls being provided with a hasp-receiving opening, and end-walls, said end-walls being provided with guiding openings, a reciprocatory slide-plate within said chambered shell, said slide-plate having its respective end-portions projecting into and from the respective guiding openings in said end-walls, a fingerpiece connected with one of the projecting end-portions of the slide-plate, a stop-member connected with the other projecting end-portion of the slide-plate, and a marginal hasp-engaging flange connected with and extending downwardly from said slide-plate, lugs connected with and extending from said slide-plate, a spring within said shell having portions thereof in engagement with said lugs, for maintaining the slide-plate in its manually released position, and means within said shell for automatically returning the slide-plate to its initial position upon entrance of the hasp into said shell.

9. A bag-frame fastener comprising a chambered shell having a top, longitudinally extending side-walls, one of said side-walls being provided with a hasp-receiving opening, and end-walls, said end-walls being provided with guiding openings, a reciprocatory slide-plate within said chambered shell, said slide-plate having its respective end-portions projecting into and from the respective guiding openings in said end-walls, a fingerpiece connected with one of the projecting end-portions of the slide-plate, a stop-member connected with the other projecting end-portion of the slide-plate, and a marginal hasp-engaging flange connected with and extending downwardly from said slide-plate, lugs connected with and extending from said slide-plate, a spring within said shell having portions thereof in engagement with said lugs, for maintaining the slide-plate in its manually released position, and an additional spring within said shell for automatically returning the slide-plate to its initial position upon entrance of the hasp into said shell.

10. In a bag-frame fastener, in combination with a hasp-member, a main shell, a slide-plate within said shell, means carried by said slide-plate with which the hasp-member is adapted to be brought into locked engagement, a pair of studs connected with and extending from said slide-plate, a spring within said shell, said spring having an angular portion extending normally between the said studs and co-operating with said slide-plate for maintaining the same in its manually released position, and means in said shell for returning said slide-plate

to its initial position and into locked engagement with the hasp-member when the hasp-member is brought into engagement with the angular portion of said spring.

- 5 11. In a bag-frame fastener, in combination with a hasp-member, a main shell, a slide-plate within said shell, means carried by said slide-plate with which the hasp-member is adapted to be brought into locked engagement, a pair of studs connected with and extending from said slide-plate, a spring within said shell, said spring having an angular portion extending normally between the said studs and co-operating with said 10 slide-plate for maintaining the same in its

manually released position, and another spring with said chamber for returning said slide-plate to its initial position and into locked engagement with the hasp-member when the hasp-member is brought into engagement with the angular portion of said first-mentioned spring. 20

In testimony, that I claim the invention set forth above I have hereunto set my hand this 11th day of August, 1924.

FRANK T. STUART.
